MERCURY SWITCH

Carl H. Larson, Elkhart, Ind., assignor to The Ad-
lake Company, a corporation of Illinois

Application October 16, 1943, Serial No. 506,494

13 Claims. (Cl. 200—97)

1

Mercury switches are commonly required for various installations subject to excessive vibration, exceedingly rapid acceleration and deceleration, or severe mechanical shock from impact or other causes. Such forces and the inertia of the switch parts create severe stress in the switch structure and sometimes seriously shorten the service life of a switch.

Metal envelope switches are particularly suitable to such difficult service conditions, due to their rugged construction, but even so, the interior structure of the switch is sometimes damaged when the service conditions are too severe.

In a displacement switch of the type in which the present invention has special utility, electrodes or other members extend inwardly from the switch envelope as cantilever structures and may break or bend permanently under severe lateral mechanical shock especially if the cantilever structures are weighted at their free ends. Thus a simple lightweight rod-like electrode surrounded by glass, ceramic or other insulating material will withstand, to a required degree, vibrations and lateral mechanical shock without breaking or cracking but may sometimes fail if burdened by carrying at its free end substantial structure for the time delay functions or structure for other purposes.

One object of the present invention is to provide a sturdy switch construction for long life under such severe service conditions as to impose excessive structural stresses. It is contemplated that the new construction will not only withstand the stresses incidental to the operation of various vehicles and heavy-duty machinery but will also stand up under such abuse as striking or dropping the switch itself. In this regard I have the concept of making one of the two electrodes of a mercury switch relatively large in cross section, preferably of open or hollow construction to straddle or enclose the other of the two electrodes in spaced relation thereto.

Such an electrode of large cross dimension has inherent structural efficiency to withstand excessive lateral stresses and may be loaded with any required switch structure without risk of failure. In some practices, the inner electrode is unburdened or at least is so lightly loaded with additional structure as to withstand all contemplated stresses without any special support. Other practices of the invention, however, are characterized by the concept of mechanically connecting the inner electrode with the outer electrode in an insulating manner whereby the

2

inner electrode is braced by the sturdy outer electrode to meet all lateral forces.

An important problem solved in some practices of my invention is to provide a mercury-leakage arrangement for time delay that may be manufactured with utmost precision and minimum wastage and, moreover, will function in a predetermined desirable manner throughout the life of the switch.

10 Heretofore, time delay by mercury leakage has been achieved by providing a metering orifice in some insulating material such as glass or a ceramic. The nature of these materials and the manufacturing methods dictated by the character 15 of these non-conducting materials have precluded precision and uniformity in the dimensions of the orifices. In some such switches the current controlled by the switch must be restricted to the small mercury stream at the orifice and the 20 resulting high local resistance causes such heating as to burn the edges of the orifice. The intense local heating is undesirable not only for its destructive effect on the material around the orifice but also because of its effect on the mercury fill.

25 My solution for the problem of producing precision orifices and of avoiding local heating is to achieve a switch combination that makes it possible to form the orifice in a metal wall. Metering orifices can be drilled in metal to exceedingly accurate dimensions and no localized high resistance to current flow can occur at an orifice in a metal wall since current can flow directly through the metal between mercury masses on 30 opposed sides of the wall.

35 A third problem met with complete success in the preferred practices of my invention is to provide a displacement-type mercury switch of predominantly metal construction that will carry 40 high-amperage loads without excessive heating of the mercury and without current flow to any 45 damaging extent along undesirable paths through the switch structure.

This problem is especially troublesome if the 45 displacement means is a magnetically actuated armature guided by the metal walls of the switch envelope, since the switch envelope is connected to one side of the circuit and current tends to flow from the envelope through the armature 50 and the mercury fill to the inner make-and-break zone of the switch. Sustained current flow substantially above 20 amperes will, in a conventional switch construction, burn the metal of the armature or even weld the armature to the 55 switch envelope.

In the present invention a conductor or an electrode of substantially lower resistivity than mercury extends from the switch envelope to points lying between the armature and the make-and-break zone to provide a path of substantially higher conductance than any path through the armature and to provide such a short mercury path as to minimize heating effect of the current on the mercury fill.

Various switch installations require various operation characteristics with respect to time delay in closing and opening the switch circuit. One concept found in certain practices of my invention is that of employing interchangeable time elements or units for mounting in the switch in a detachable manner at an advanced stage of manufacture whereby nearly complete switch subassemblies may be stocked and then completed by the final addition of timing means selected in accord with a particular demand.

It will be apparent that all of the above-mentioned features may be embodied in the construction of a switch electrode. That is to say, a switch electrode may be of hollow construction and of substantial cross-sectional dimension to carry burdensome structure and yet withstand lateral stresses; the electrode may serve as a structural brace for an inner, less sturdy electrode; the electrode may provide the metal wall for a metering orifice; the electrode may extend between points of the armature and the make-and-break zone to provide a relatively short mercury path for current flow; and, finally, the same electrode may incorporate a detachable time unit selected from a stock of various time units.

The above and other objects and advantages will be apparent in my following detailed description taken with the accompanying drawing.

In the drawing which is to be regarded as merely illustrative,

Fig. 1 is a longitudinal sectional view of one form of my invention;

Fig. 2 is a transverse section taken as indicated by the line 2—2 of Fig. 1; and

Fig. 3 is a longitudinal sectional view of a second form of the invention.

The form of the invention shown in Figs. 1 and 2 includes a cylindrical switch envelope 10 inclosing a mercury fill 11 and a displacement means generally designated 12, the displacement means being in the form of an armature for electromagnetic switch actuation. In the normal or de-energized state of the switch, the displacement means 12 is free to float partially submerged in the mercury fill as shown in Fig. 1. Energization of an exterior electromagnetic means generally designated 13 draws the displacement means 12 downward thereby to raise the level of the mercury fill in a well-known manner. When the liquid level of the mercury fill rises, a conducting bridge of mercury is formed between what may be termed an inner electrode generally designated 15 and an outer electrode generally designated 18.

The electromagnetic means 13 may comprise a coil 17 having an iron circuit 18 and providing an axial opening to receive and retain the switch envelope 10. In the particular construction shown in the drawing, the iron circuit includes two circular pole pieces 20 defining an air gap 21 and the switch envelope 10 is mounted in proper position relative to the air gap by a rubber collar 22 tightly embracing an insulating sleeve 23. The insulating sleeve 23, which may be Bakelite, completely surrounds the switch

envelope 10 and is suitably bonded thereto. Preferably a bracket 25 is adjustably mounted on the iron circuit 18 by a machine screw 26 to engage the rubber collar 22 as shown.

The switch envelope 10 comprises a cylindrical wall 27, an upper cap 28 and a lower cap 30. The cylindrical wall 27, which may be polished on its inner surface to minimize frictional movement of the displacement means 12, should be made of metal that is both nonmagnetic and resistant to wetting by mercury. A suitable metal, for example, is a stainless steel known as "18-8 steel" having besides iron, approximately 18% chromium and 8% nickel.

The upper cap 28 may be a metal disc or a pressed sheet metal member with an upturned flange 31 to fit inside the cylindrical envelope wall 27. The joint between the cap 28 and the cylindrical wall 27 may be sealed in any suitable manner, for example, by welding as indicated at 32.

In my preferred construction, the upper cap 28 is provided with a central bore 33 normally sealed by a headed pin or plug 35. In the course of manufacture air may be evacuated from the switch envelope through the bore 33 and then a suitable inert gas or mixture of inert gases may be introduced through the same bore to fill the envelope under pressure. The gas or gases may be selected from a group comprising hydrogen, nitrogen, argon and helium hydride. After the gas has been introduced to the desired pressure, the head of the pin or plug 35 is welded to seal the bore 33.

The lower cap 30 may likewise be a metal disc or pressed sheet metal member with a flange 36 to fit inside the cylindrical envelope wall 27 and the joint may likewise be sealed by welding as indicated at 31. The cap 30 has a central aperture surrounded by a cylindrical flange 38 to embrace a body of insulating material 40. In the present construction, the insulating material 40 is part of the structure of the inner electrode 15, the insulating material forming a tubular wall 41 around an inner electrode member or electrode proper 42.

It is requisite that the materials of the cap 30, insulating body 40, and the electrode member 42 all have substantially the same coefficient of thermal expansion to maintain effective sealing relationships under varying temperature conditions. In my preferred embodiment of the invention the electrode body 42 is made of molybdenum, the insulating body 40 is a hard glass such as Corning G705AJ fused both to the electrode member and to the cap 30, and the cap is fabricated from a metal known to the trade as "Kovar," an alloy manufactured by the Stupakoff Laboratories, Pittsburgh, Pennsylvania.

One wire 43 of the circuit to be controlled by the switch may be soldered to the cap 30 as shown or any place on the switch envelope, and the other wire 45 of the circuit may be soldered to the external end of the electrode member 42.

The tubular glass insulating wall 41 terminates short of the upper end of the electrode member 42 so that the electrode member has an end portion exposed for mercury contact in the make-and-break zone of the switch between the minimum and maximum levels of the mercury fill. It is desirable that this end portion of the electrode be continuously immersed in a small pool of mercury and to this end I mount a cup 46 on the upper end of the tubular insulating wall 41 to trap a pool 49 of mercury. It is essential that

the material employed in fabricating such a cup be efficiently bonded to the tubular glass wall 41 and have the same coefficient of thermal expansion. The cup may be made, for example, of a ceramic known as Alundum manufactured by the Norton Company, Worcester, Massachusetts and may be simply fused to the upper end of the tubular wall 41, in accordance with the teachings of my Reissue Patent #21,661 issued December 17, 1940.

In designing the outer electrode 16 the first consideration with respect to meeting destructive forces is to form the outer electrode with a relatively wide base for anchorage to the metal cap 30 and to make the electrode relatively wide in cross section. To this end, the outer electrode may be of open or frame construction or may be of hollow construction. In the present form of the invention, the outer electrode is of hollow or closed construction and preferably is cylindrical in configuration so that it may meet forces from all lateral directions with equal efficiency.

If the switch is to operate with time delay the required time delay means may be carried by the structurally efficient outer electrode without risk of overburdening the electrode. Commonly, the time delay means provides a fluid passage for restricted gas flow into or out of a gas trap and/or a fluid passage or mercury leak orifice for controlling the rate of mercury flow to or from the make-or-break zone within the configuration of the outer electrode. In this first form of my invention restricted gas flow determines the extent of the time delay action.

In the switch construction shown in Fig. 1, the outer electrode 16 comprises a tubular electrode member 47 having relatively large mercury ports 48 near its base. The tubular electrode member 47 may be mounted on the lower cap 30 by screw-threaded engagement with upturned circular flange 38 of the cap and may, if desired, be additionally welded to the cap. Any suitable conducting material may be employed for the tubular electrode member 47. For example, I may employ the previously mentioned stainless steel or I may use plain or chromium plated cold rolled steel. For high amperage loads, it may be desirable to use a metal such as copper having substantially lower resistivity than iron or steel thereby highly favoring current flow to the make-and-break zone through the tubular electrode member 47 rather than through the displacement means 12.

The desired gas trap may be formed by or in the tubular electrode member 47 or may be mounted on the electrode member. Fig. 1 shows a gas trap 50 in the form of a bell-shaped member cut away to provide relatively large mercury ports 51 with upper edges 52, which upper edges are preferably substantially horizontal. Any expedient may be employed for mounting the gas trap 50 on the tubular electrode member 47 but in my preferred construction I simply thread the gas trap onto the upper end of the electrode member as shown in Fig. 1. The material employed for the gas trap may be the same metal as the material of the tubular electrode 47.

The passage means for restricted gas flow from the interior of the trap 50 may be in the form of a porous plug 53 mounted in a tubular port 55 at the upper end of the gas trap. Any suitable porous substance may be employed for the plug, for example, the previously mentioned ceramic material known as Alundum which is available in several grades including dense, medium and coarse.

The inner electrode 15 is constructed as described, and only lightly burdened by the small ceramic cup 46, will withstand without damage relatively severe lateral mechanical forces encountered in many installations. To meet exceptionally destructive lateral forces, however, it is desirable to reinforce or embrace the inner electrode and a feature of a preferred practice of my invention is the concept of accomplishing this end simply by mechanically connecting the inner electrode with the surrounding outer electrode. For example, bracing of the inner electrode may be accomplished by forming the tubular insulating wall 41 with a circumferential bead 56 to support a reinforcing collar or spider 57. As indicated in Figs. 1 and 2, the spider 57 may be in the form of a ring of ceramic material or glass dimensioned to fit snugly against the surrounding tubular electrode member 47 and cut away on its periphery to provide passages 58 for free mercury flow. In effect, the spider 57 structurally unites the outer electrode with the inner electrode to give the inner electrode the benefit of strength inherent in the tubular configuration of the outer electrode.

The displacement means or armature 12 may comprise a cylinder 60 of suitable ferromagnetic material such as iron and may be adapted for guidance by the surrounding switch envelope. In the present construction, for example, the cylinder 60 is formed with integral radial flanges 61 at its top and bottom, each of the flanges being cut away as shown in Fig. 2 to provide guiding lugs 62 and intervening mercury flow passages 63.

Preferably, I employ coil springs 65 of non-magnetic material at the opposite ends of the ferromagnetic cylinder 60 to serve as buffer means. If either of the caps 28 and 30 is of ferromagnetic material, such coil springs are especially desirable to prevent the displacement means 12 from clinging to the cap magnetically. The term "displacement means" is to be understood as applying to the ferromagnetic cylinder 60 or as covering the cylinder together with the coil springs 65.

In some practices of my invention such as the practices illustrated in the present disclosure, I place a wall of insulating material such as glass or some suitable ceramic between the cup 46 and the metal of the displacement means 12, an important purpose of the insulating wall being to lengthen the minimum possible path of current flow through mercury from the displacement means to the mercury pool 49 in the cup. Any current flowing between the metal of the displacement means and the mercury pool in the cup must pass around the ends of such an insulating wall. Obviously, such an insulating wall may be fixedly mounted in the switch envelope in any suitable manner or may be carried by the ferromagnetic cylinder 60. In my present construction, the insulating wall is in the form of a cylinder or tube 66 mounted inside the ferromagnetic cylinder 60 in the manner of a liner. Preferably, the insulating cylinder 66 extends beyond the opposite ends of the ferromagnetic cylinder 60 but terminates short of the unrestrained extent of the two coil springs 65. The coil springs may tightly embrace the ends of the insulating cylinder 66 as means for holding the insulating cylinder 66 assembled to the surrounding ferromagnetic cylinder 60.

In the preferred practice of my invention another expedient employed to prevent current flow between the switch envelope and the displace-

ment means is the coating of the displacement means with a suitable high resistance material selected from materials that will not react with the mercury. For example, I may coat at least the peripheral surface of the displacement means with oxide of iron as stated in my Patent 2,121,804 issued June 28, 1938. When such a coating is formed on the displacement means, the resistance of the displacement means multiplies to discourage current flow therethrough.

The operation of the described switch may be readily understood from the foregoing description. In Fig. 1 the coil 17 is de-energized, the displacement means 12 is at its upper position by virtue of its buoyancy with respect to the mercury fill, and the mercury fill is at its minimum liquid level 67 below the horizontal edges 52 of the gas trap mercury ports 51. No current can flow through the switch because the major mercury body is separated from the mercury pool 49. 20

Energization of the electromagnet draws the displacement means 12 to its lower position thereby displacing the mercury fill to a maximum mercury level, for example, the maximum level indicated by dotted lines 68. The maximum mercury level is of course substantially above the level of the mercury cup 46 and the sudden rise of the mercury outside of the tubular electrode to the maximum level 68 causes the mercury inside the gas trap 50 to rise to an initial level 30 slightly above the horizontal port edges 52, gas in the trap being compressed by hydrostatic pressure derived from the mercury column outside the trap. The resulting pressure differential between the gas in the trap and the gas 35 above the trap causes gas to flow upward out of the trap at a retarded rate governed by the flow capacity of the porous plug 53. Eventually the gas volume inside the trap diminishes sufficiently to permit the mercury column inside the 40 trap to rise above the lip of the cup 46 and merge with the mercury pool 49 to close the switch circuit.

Upon subsequent de-energization of the electromagnet, the displacement means rises immediately to its original floating position with simultaneous drop of the mercury level outside the trap. As soon however, as the mercury level outside the trap drops below the horizontal port edges 52, gas is free to enter the gas trap laterally and the mercury column inside the trap thereupon collapses suddenly to open the switch circuit in an instantaneous manner.

From the manufacturing standpoint, an important feature of the described construction is that subassemblies may be fabricated and stocked to be completed as demand arises and in accord with time delay characteristics dictated by the demand. For example, such a subassembly may comprise the cylindrical wall 21 of the envelope, 45 the lower cap 36 welded thereto and the completed inner electrode 15 carried by the lower cap 30. The only internal switch structure missing from the subassembly would be either the gas trap 50 alone or the gas trap together with the tubular electrode member 41. At the time of final assembly, a gas trap 50 would be selected from a diverse stock of gas traps to provide the time delay action specified by the purchaser of the switch, the gas trap or the gas trap together 70 with the tubular electrode being simply threaded onto the subassembly.

The second form of my invention shown in Fig. 3 is largely similar to the first described form, as indicated by the use of corresponding

5 numerals to designate corresponding parts. In this second form of the invention, I employ an outer electrode 70 that consists of a simple metal tube provided with a mercury leak orifice 72 below the normal level 73 of the mercury fill. In the particular construction shown in Fig. 3, the upper end of the tubular electrode 70 is cut at a slant to provide an overflow lip 75 below the maximum level of the mercury fill.

10 Upon energization of the electromagnetic means 13, the displacement means 12 is drawn downward to cause the mercury level to rise above the lip 75 whereupon the mercury flows into the outer electrode 70 to merge with the mercury pool 49 and thereby close the switch circuit.

Upon subsequent energization of the electromagnetic means 13 to permit the displacement means to return to the original position shown in Fig. 3, the mercury level outside the electrode 70 drops initially below the normal level 73 but mercury within the electrode 70 is temporarily trapped and can drop in level only at a retarded rate determined by the area of the orifice 72 and the differential in mercury levels. Eventually the mercury inside the electrode 70 drops below the lip of the mercury cup 46 to open the circuit. 20

25 The invention obviously may be employed in slow and fast acting switches within the teachings of this disclosure.

30 In switches constructed as described herein, the outer electrodes are hollow but being of relatively large diameter may nevertheless have relatively large cross-sectional area and therefore the capacity to carry considerable amperage. The wall of a hollow electrode may be relatively thick if desired.

35 It is to be noted especially that the metal wall of the electrode lies between the surrounding displacement means and the central cup. The significance of this relationship may be appreciated by comparing the normal path of current flow through the outer electrode with any path of current flow through the displacement means. The outer electrode provides an all-metal path for current flow from the switch envelope to the level of the cup leaving only the short radial distance between the electrode and the cup for current flow through mercury. In contrast, the displacement means is not connected with the metal envelope to form a continuous metal path and, moreover, all mercury paths from the displacement means to the central cup are excessively long.

40 It is apparent that even under high amperage loads no damaging current will flow from the switch envelope to the armature. In effect, the outer hollow electrode is a conductor shield between the cylindrical wall of the switch envelope and the mercury cup, the conductor shield being necessarily at the same instant potential as the cylindrical wall of the envelope to preclude current flow radially between the envelope and the mercury pool in the cup.

45 Selected embodiments of the invention have been described in specific detail herein for the purpose of illustration and to teach the principles involved. Various changes and substitutions may be made under my basic concepts and therefore the following claims are to be construed as broadly as the prior art will permit.

I claim:

50 1. In a mercury switch, a metal switch envelope for connection with one side of a switch circuit, a mercury fill, a metal displacement means of hollow configuration in said envelope, means

to shift said displacement means thereby to cause the mercury level to rise and fall in a make-and-break zone inside said displacement means to close and open the switch circuit, and a metal conductor inside said displacement means spaced therefrom, said metal conductor extending around said make-and-break zone and being connected with said envelope to have the same instant potential as the envelope for preventing damaging current flow between the envelope and the displacement means.

2. In a mercury switch, a switch envelope, a mercury fill, displacement means movable to vary the liquid level of the mercury fill, a first electrode in said envelope exposed for mercury contact above the minimum liquid level of the mercury fill, a second electrode extending inward at least approximately as far as the inner end of the first electrode, the said second electrode being of relatively large cross section to withstand lateral mechanical shocks, said second electrode enclosing a space for mercury extending on opposite sides of said first electrode, and means extending across said space at a level substantially above the bottom of the space to mechanically interconnect the two electrodes to brace the first electrode against lateral mechanical shocks, said interconnecting means permitting fluid flow through its level from above and below.

3. In a mercury switch, a switch envelope, a mercury fill, displacement means movable to vary the liquid level of the mercury fill, a first electrode in said envelope exposed for mercury contact above the minimum liquid level of the mercury fill, a second electrode extending inward at least approximately as far as the inner end of the first electrode, the said second electrode being of relatively large cross section to withstand lateral mechanical shocks, said second electrode defining a space for mercury surrounding said first electrode, there being restricted fluid communication between said space and the exterior of said second electrode to retard changes in the mercury level in the space in response to changes in the mercury level outside the second electrode, and means extending across said space at a level substantially above the bottom of the space to mechanically interconnect the two electrodes to brace the first electrode against lateral mechanical shocks, said interconnecting means permitting fluid flow through its level from above and below.

4. In a mercury switch, a switch envelope, a body of mercury partially filling the envelope, a body of gas above the mercury, displacement means movable to vary the liquid level of the mercury, a first electrode in said envelope exposed for mercury contact above the minimum liquid level of the mercury, and a second hollow electrode defining a space surrounding said first electrode above the minimum liquid level of the mercury, there being sufficiently restricted fluid communication between an upper portion of said space and the exterior of the second electrode for sufficiently restricted gas flow out of the space to retard rise in mercury level in the space responsive to rise in mercury level outside the second electrode, there being relatively free fluid communication between a lower portion of said space and the exterior of the second electrode for rapid mercury flow into and out of the space at said lower portion.

5. In a mercury switch, a switch envelope, a body of mercury partially filling the envelope, a body of gas above the mercury, displacement

means movable to vary the liquid level of the mercury, a first electrode in said envelope exposed for mercury contact above the minimum liquid level of the mercury, and a second hollow electrode surrounding said first electrode and defining a vertically extensive space extending above and below the minimum liquid level of the mercury, there being relatively free fluid communication between said space and the exterior of said second electrode at an intermediate level above the minimum mercury level and at a lower level to cause the mercury level in the space to rise rapidly to said intermediate level in response to rise in the mercury level outside the second electrode, there being sufficiently restricted fluid communication between said space and the exterior of the second electrode at a level substantially above the minimum mercury level for sufficiently restricted gas flow out of the space to retard rise in mercury level from said intermediate level in response to rise in the mercury level outside the second electrode.

6. In a mercury switch, a switch envelope, a body of mercury partially filling the envelope, a body of gas above the mercury, displacement means movable to vary the liquid level of the mercury, a first electrode in said envelope exposed for mercury contact above the minimum liquid level of the mercury, and a second electrode having a wall forming a gas trap at the level at which mercury electrically bridges the two electrodes, said trap having a sufficiently restricted gas vent to retard the escape of gas thereby to retard the rise of mercury in the trap to said bridging level, said trap being apertured at a lower level below said bridging level for the free inflow of gas and free outflow of mercury to cause the mercury column in the trap to collapse suddenly when the mercury outside the trap falls to said lower level.

7. In a mercury switch, a switch envelope, a mercury fill, displacement means movable to vary the liquid level of the mercury fill, a first electrode in said envelope exposed for mercury contact above the minimum liquid level of the mercury fill, a second electrode spaced from said first electrode, said second electrode extending on opposite sides of said first electrode to provide a relatively wide cross section for withstanding lateral mechanical shocks, and a gas trap supported at the level at which mercury electrically bridges the two contacts, said trap having a sufficiently restricted gas vent to retard the escape of gas thereby to retard the rise of mercury in the trap to said bridging level, said trap being apertured at a lower level below said bridging level for the free inflow of gas and free outflow of mercury to cause the mercury column in the trap to collapse suddenly when the mercury outside the trap falls to said lower level.

8. In a mercury switch, a switch envelope, a mercury fill, displacement means movable to vary the liquid level of the mercury fill, a first electrode in said envelope exposed for mercury contact above the minimum liquid level of the mercury fill, a second electrode spaced from said first electrode, said second electrode extending on opposite sides of said first electrode to provide a relatively wide cross section for withstanding lateral mechanical shocks, and a gas trap supported at the level at which mercury electrically bridges the two contacts, said trap having a sufficiently restricted gas vent to retard the escape of gas thereby to retard the rise of mercury in the trap to said bridging level, said trap being

apertured at a lower level below said bridging level for the free inflow of gas and free outflow of mercury to cause the mercury column in the trap to collapse suddenly when the mercury outside the trap falls to said lower level, said gas trap being structurally separate from and attachable to said second electrode whereby in the course of manufacture of the switch, selection may be made from a variety of gas traps for various operating characteristics.

9. In a mercury switch, a switch envelope, a mercury fill, displacement means movable to vary the liquid level of the mercury fill, a first upright electrode in said envelope exposed for mercury contact above the minimum liquid level of the mercury fill, a second upright electrode extending upward at least as far as the upper end of the first electrode, said second electrode extending on opposite sides of said first electrode to provide a relatively wide cross section for withstanding lateral mechanical shocks, non-conducting means mechanically interconnecting said electrodes near the bottom of said envelope, and a non-conducting bridge spaced substantially above said non-conducting means mechanically interconnecting said two electrodes to brace the first electrode against lateral mechanical shocks.

10. In a mercury switch, a metal switch envelope for connection with one side of a switch circuit, a mercury fill, a metal displacement means of hollow configuration in said envelope, said displacement means being shaped and dimensioned for guidance by the envelope, means to shift said displacement means thereby to vary the liquid level of the mercury fill, a first electrode for the other side of the circuit having a portion exposed for mercury contact between the minimum and maximum liquid levels of the mercury fill, and a second electrode of lower resistivity than mercury connected with said envelope and extending between said displacement means and said exposed portion of the first electrode to provide a mercury path to the exposed portion substantially shorter than mercury paths to the exposed portion from any points on said displacement means whereby said second electrode cooperates with the mercury fill to provide a path from said envelope to said exposed portion of substantially greater conductance than any path through said displacement means, thereby preventing damaging current flow between the envelope and the displacement means under relatively high amperage switch loading.

11. In a mercury switch, a closed metal en-

velope including a base through which a relatively long glass insulated conductor is hermetically sealed at its lower end with its upper end exposed to serve as an electrode, a mercury fill, a magnetically actuated displacer for shifting the mercury fill into and out of contact with said exposed electrode, said glass insulated conductor, because of its length, being relatively fragile and subject to breakage particularly when subjected

10 to lateral shock, and a tubular metallic member rigidly fixed to the envelope base, telescoped over the said conductor, and limiting lateral movement of the upper end of the conductor to amounts which will not cause cracking of the glass on the said conductor.

12. In a mercury switch, a closed metal envelope including a base, an insulated conductor hermetically sealed through the base and having its upper end exposed to serve as an electrode,

20 a mercury fill, a metal displacer magnetically actuated to shift the mercury fill into and out of contact with the said electrode, a tubular metallic member having substantially greater conductivity than mercury rigidly fixed to the

25 base, telescoped over the said conductor, and extending upwardly to a point relatively close to said exposed electrode, said envelope with its base, tubular metallic member and mercury fill being adapted to be electrically connected to one

30 side of an electric circuit and said conductor to the other side, said tubular member, because of its proximity to said exposed electrode and because of its superior conductivity relative to mercury, substantially reducing the flow of current

35 which takes place from the envelope to the exposed electrode through the displacer when the tubular metallic member is eliminated.

13. In a mercury switch, the combination of a switch envelope, a mercury fill, spaced electrodes

40 in the envelope including an insulated conductor sealed through the base of the envelope and projecting upwardly through the mercury fill with the upper end of the conductor exposed to form one of said electrodes, a mercury displacer for

45 shifting the mercury fill to make and break an electrical circuit through said electrodes, and a gas leakage time delay element over said exposed electrode, said time delay element being mounted on and supported solely by a tubular sleeve telescoped over and spaced from the insulated conductor, said sleeve being rigidly affixed to the

50 switch envelope.

CARL H. LARSON.
